UNITED STATES PATENT OFFICE

JAMES WALTER BEATTIE, OF HOLLYWOOD, CALIFORNIA

DESIGN FOR A LIGHT SCREEN

Application filed September 8, 1930. Serial No. 36,900. Term of patent 7 years.

To all whom it may concern:

Be it known that I, JAMES WALTER BEATTIE, a citizen of the United States, residing at Hollywood, in the county of Los Angeles and State of California, have invented a new, original, and ornamental Design for a Light Screen, of which the following is a specification, reference being had to the ac-

companying drawing, forming part thereof.

The figure is a plan view of a light screen, showing my new design. The design is of no appreciable thickness.

I claim:

The ornamental design for a light screen, as shown and described.

JAS. WALTER BEATTIE.
